UNITED STATES PATENT OFFICE

2,692,773

AUTOMATIC SELF-CENTERING ROLL

Edwin T. Lorig, Ross Township, Allegheny County, Pa., assignor to United States Steel Corporation, a corporation of New Jersey

Application March 8, 1951, Serial No. 214,493

21 Claims. (Cl. 271—2.6)

1

This invention relates to an automatic self-centering roll and is a continuation-in-part of my copending application, Serial No. 145,648, filed February 23, 1950, now Patent No. 2,593,158.

It is an object of my invention to provide an automatic self-centering roll which is particularly suitable for high speeds such as 4000 feet per minute.

Another object is to provide such a roll which is particularly suitable for long bodied rolls regardless of their diameter.

These and other objects will be more apparent after referring to the following specification and attached drawings, in which:

Figure 1 is a transverse sectional view of a roll of my invention;

Figure 2 is a view taken on the line II—II of Figure 1;

Figure 3 is a view taken on the line III—III of Figure 1;

Figure 4 is a view, similar to Figure 1 showing a slight modification of my invention;

Figure 5 is a fragmentary view taken on the line IV—IV of Figure 4;

Figure 6 is a view, similar to Figure 1, showing a further modification of my invention;

Figure 7 is a view taken in the direction of the arrow 7 of Figure 6;

Figure 8 is a view taken on the line VIII—VIII of Figure 6;

Figure 9 is a fragmentary view showing a slight modification of Figure 6;

Figure 10 is a view, similar to Figure 1, showing another modification of my device;

Figure 11 is a fragmentary view taken on the line XI—XI of Figure 10;

Figure 12 is a fragmentary view showing the roll of Figure 10 in a different position;

Figure 13 is a sectional view, similar to Figure 1, showing another embodiment of my invention;

Figure 14 is a sectional view taken on the line XIV—XIV of Figure 13;

Figure 15 is a sectional view, similar to Figure 13, showing a slight modification thereof;

Figure 16 is a sectional view taken on the line XVI—XVI of Figure 15; and

Figure 17 is a fragmentary view of an element of the rolls of Figures 13 and 15.

Referring more particularly to Figures 1, 2 and 3 of the drawings, reference numeral 2 indicates a shaft supported in bearings 4. Keyed to each end of the shaft 2, adjacent the bearings 4, is a web portion 6 having a shoulder 8 around its periphery. A pair of frusto conical rims 10 surround the shaft 2 with their large diameter ends adjacent each other and their small diameter ends bearing against the shoulder 8. The ad-

2

jacent ends of the rims 10 have inwardly extending flanges 12 thereon. The web 6 is provided with four equally spaced holes 14 around its periphery which are in alignment with holes 16 in the flanges 12. Tension bolts or rods 18 pass through the aligned holes 14 and 16. There is close clearance between the tension bolts 18 and the holes 16 and a greater clearance between the tension bolts 18 and the holes 14. If desired the small diameter ends of the rims 10 may be welded to the web 6. While four tension rods 18 are shown, three or more such rods may be used depending on the size of the centering roll and the load to be carried. The tensioning rods should be pulled up tight with approximately the same tension on each rod. The amount of tension may be varied in order to vary the deflection of the roll under load. When a strip S to be centered passes over or partially around the roll, the portion of the rims in contact with the strip deflects inwardly toward the center of rotation of the roll. The bolt or bolts 18 opposite the line of load application are stretched slightly to permit roll deflection.

The roll shown in Figures 4 and 5 is identical with that of Figure 1 except that a groove 20 is provided in the large diameter end of each of the rims 10 for receiving a gasket 22 which prevents infiltration of oil or other material into the interior of the roll.

In the embodiment of my invention shown in Figures 6 to 8, a shaft 24 is mounted in bearings 26. The shaft 24 has a web portion 28 keyed to each end thereof. A pair of frusto conical rims 30 are mounted on the webs 28 with their large diameter ends adjacent each other. The inner end of each of the rims 30 is provided with an undercut portion 32 for receiving a ring 34 which has a number of holes 36 spaced around its periphery for receiving tension bolts 38. The outer end of each of the rims 30 has a tapered counterbored portion 40 for receiving a ring 42 which has a number of holes 44 therein. Part of the holes 44 are in alignment with the holes 36 in the rings 34. The tension bolts 38 pass through the holes 36 and 44. Each of the web portions 28 are provided with holes 46 for receiving the heads and nuts of the bolts 38. Each of the rim portions 28 is also provided with a number of threaded openings 48 which are in alignment with holes 50 in the rings 42. A screw 52 is threaded into the openings 48 with its ends extending into the hole 50 in order to cause the rims 30 to rotate in unison. The operation of this roll is essentially the same as shown in Figure 1.

Figure 9 shows a slight modification of the roll of Figure 6 in which the rings 34 are omitted and

the adjacent ends of the rims 30 are provided with a male and female joint 54 in order to hold the parts in alignment.

Figures 10 to 12 show another embodiment of my invention in which frusto conical rims 56 and 58 are supported on shafts or trunnions 60 and 62 for rotation in bearings 64 and 66. The large diameter end of the rim 56 is provided with a tongue 68 which is received in a complementary groove 70 in the large diameter end of rim 58. The adjacent ends of the rims 56 and 58 are provided with radial flanges 72 having a number of aligned holes 74 therein for receiving bolts 76. A spring washer 78 is received under the head of each of the bolts 76. Hand holes 80 are provided in the web portions of the rims 56 and 58 to permit insertion of the bolts 76. The bolts 76 hold the two halves of the roll together with sufficient clearance between the bolts and the holes to prevent binding. The spring washer 78 provides for a slight elongation between the head and the nut of the bolts to secure a slight deflection of the roll under load. The bolts also cause the rims 56 and 58 to rotate in unison. The tongue and groove arrangement 68 and 70 maintains the rims of the roll in alignment. The operation of this roll is essentially the same as that of the other embodiments. When not under load, there is a uniform clearance 82 between the ends of the two rims. When load is applied to the roll, a portion of the roll adjacent the load will have very little clearance between the rim portions, while the diametrically opposite portion of the roll will have larger clearance as shown in Figure 12. This figure also shows how the spring washer 78 is depressed to permit deflection of the roll.

Figures 13 and 14 show another embodiment of my invention in which a roll shaft 84 is mounted for rotation in bearings 86. Web portions 88 and 90 are keyed to the ends of shaft 84. A frusto conical rim portion 92 is mounted on web portion 88 and a similar frusto conical rim portion 94 is mounted on web portion 90. Radial ring members 96 and 98 are welded to the rim portions 92 and 94, respectively, in spaced apart relationship. A rubber sandwich ring 100 extends around the shaft between the rings 96 and 98. A bronze aligning ring 102 surrounds the periphery of the sandwich ring 100 between the rings 96 and 98. As shown in Figure 17, the aligning ring 102 has a plurality of transverse slots 104 therein which extend substantially half-way through the width of the ring with alternate slots facing in opposite directions. A sliding joint 106 is provided between the ends of the ring 102. The sandwich ring is held in place and the two parts of the roll are held together by means of bolts 108 which extend through holes in the rings 96, 98 and 100 to the web portions 88 and 90. As clearly shown, alternate bolts 108 are fastened to web portion 88 and the remaining bolts 108 are fastened to the web 90. This roll operates in substantially the same manner as that shown in Figure 1 and is particularly suitable for heavy loads. The rubber sandwich ring 100 permits limited deflection of the roll surface by compression against the shaft 84 under load. The aligning ring 102 holds the halves of the roll shaft in alignment while rotating under load.

Figures 15 and 16 show a slight modification of the roll of Figure 13. This roll is identical with the roll of Figure 13 except that the tension bolts 108 are replaced by short tension bolts 110 which pass through the rings 96, 98 and 100.

While several embodiments of my invention have been shown and described, it will be apparent that other adaptations and modifications may be made without departing from the scope of the following claims.

I claim:

1. Apparatus for positioning a moving object comprising a pair of coaxially opposed frustoconical rotatable rims over which the object passes in a direction transverse to the axes of the rims, the large diameter ends of said rims being adjacent each other, spaced coaxial shaft sections, a shaft portion connecting said shaft sections, a shaft extension for at least one of said shaft sections extending outwardly beyond said rims and adapted to be supported in bearing means, the large diameter ends of said rims being movable toward the axis of said shaft sections progressively at the points or lines of contact with the moving object on the approach side, an operative connection between the small diameter end of each of said rims and the adjacent shaft sections, means extending inwardly from each of said rims, and spaced apart tension bolts extending substantially parallel to the axis of said shaft sections through said last named means for urging the large diameter ends of said rims toward each other.

2. Apparatus for automatically centering a moving object according to claim 1, in which means are provided for keeping the outer surfaces of the large diameter ends of the rims in alignment.

3. Apparatus for positioning a moving object comprising a pair of coaxially opposed frustoconical rotatable rims over which the object passes in a direction transverse to the axes of the rims, the large diameter ends of said rims being adjacent each other, spaced coaxial shaft sections, a shaft portion connecting said shaft sections, a shaft extension for at least one of said shaft sections extending outwardly beyond said rims and adapted to be supported in bearing means, the large diameter ends of said rims being movable toward the axis of said shaft sections progressively at the points or lines of contact with the moving object on the approach side, an operative connection between the small diameter end of each of said rims and the adjacent shaft section, said connection including a web portion for supporting the small diameter end of each of said rims, and spaced apart tension bolts extending substantially parallel to the axis of said shaft sections through said web portions.

4. Apparatus for automatically centering a moving object according to claim 3, in which means are provided for keeping the outer surfaces of the large diameter ends of the rims in alignment.

5. Apparatus for positioning a moving object comprising a pair of coaxially opposed frustoconical rotatable rims over which the object passes in a direction transverse to the axes of the rims, the large diameter ends of said rims being adjacent each other, spaced coaxial shaft sections, a shaft portion connecting said shaft sections, a shaft extension for at least one of said shaft sections extending outwardly beyond said rims and adapted to be supported in bearing means, the large diameter ends of said rims being movable toward the axis of said shaft sections progressively at the points or lines of contact with the moving object on the approach side, an operative connection between the small diameter end of each of said rims and the adjacent shaft sec-

tion, said connection including a web portion for supporting the small diameter end of each of said rims, a flange extending inwardly from the large diameter end of each of said rims, and spaced apart tension bolts extending substantially parallel to the axis of said shaft sections through said web portions and said flanges.

6. Apparatus for automatically centering a moving object according to claim 5, in which means are provided for keeping the outer surfaces of the large diameter ends of the rims in alignment.

7. Apparatus for positioning a moving object comprising a pair of coaxially opposed frustoconical rotatable rims over which the object passes in a direction transverse to the axes of the rims, the large diameter ends of said rims being adjacent each other, spaced coaxial shaft sections, a shaft portion connecting said shaft sections, a shaft extension for at least one of said shaft sections extending outwardly beyond said rims and adapted to be supported in bearing means, the large diameter ends of said rims being movable toward the axis of said shaft sections progressively at the points or lines of contact with the moving object on the approach side, an operative connection between the small diameter end of each of said rims and the adjacent shaft section, said connection including a web portion for supporting the small diameter end of each of said rims, a ring adjacent each of said web portions, spaced apart tension bolts extending substantially parallel to the axis of said shaft sections through said rings, and driving means connecting each of said web portions to the ring adjacent thereto.

8. Apparatus for automatically centering a moving object according to claim 7, in which means are provided for keeping the outer surfaces of the large diameter ends of the rims in alignment.

9. Apparatus for positioning a moving object comprising a pair of coaxially opposed frustoconical rotatable rims over which the object passes in a direction transverse to the axes of the rims, the large diameter ends of said rims being adjacent each other, spaced coaxial shaft sections, a shaft portion connecting said shaft sections, a shaft extension for at least one of said shaft sections extending outwardly beyond said rims and adapted to be supported in bearing means, the large diameter ends of said rims being movable toward the axis of said shaft sections progressively at the points or lines of contact with the moving object on the approach side, an operative connection between the small diameter end of each of said rims and the adjacent shaft section, said connection including a web portion for supporting the small diameter end of each of said rims, a ring adjacent each of said web portions, a ring bearing against the inner surface of each of the large diameter end of said rims, spaced apart tension bolts extending substantially parallel to the axis of said shaft sections through said rings, and driving means connecting each of said web portions to the ring adjacent thereto.

10. Apparatus for automatically centering a moving object according to claim 9, in which means are provided for keeping the outer surfaces of the large diameter ends of the rims in alignment.

11. Apparatus for positioning a moving object comprising a pair of coaxially opposed frustoconical rotatable rims over which the object

passes in a direction transverse to the axes of the rims, the large diameter ends of said rims being adjacent each other, spaced coaxial shaft sections, a shaft portion connecting said shaft sections, a shaft extension for at least one of said shaft sections extending outwardly beyond said rims and adapted to be supported in bearing means, the large diameter ends of said rims being movable toward the axis of said shaft sections progressively at the points or lines of contact with the moving object on the approach side, an operative connection between the small diameter end of each of said rims and the adjacent shaft section, said connection including a web portion for supporting the small diameter end of each of said rims, a ring adjacent each of said web portions, and spaced apart tension bolts extending substantially parallel to the axis of said shaft sections through said rings.

20 12. Apparatus for automatically centering a moving object according to claim 11, in which means are provided for keeping the outer surfaces of the large diameter ends of the rims in alignment.

25 13. Apparatus for positioning a moving object comprising a pair of coaxially opposed frustoconical rotatable rims over which the object passes in a direction transverse to the axes of the rims, the large diameter ends of said rims being adjacent each other, spaced coaxial shaft sections, a shaft portion connecting said shaft sections, a shaft extension for at least one of said shaft sections extending outwardly beyond said rims and adapted to be supported in bearing means, the large diameter ends of said rims being movable toward the axis of said shaft sections progressively at the points or lines of contact with the moving object on the approach side, an operative connection between the small diameter end of each of said rims and the adjacent shaft section, said connection including a web portion for supporting the small diameter end of each of said rims, an inwardly extending flange fastened to each of said rims a short distance from the large diameter end thereof, an elastic ring between said flanges, and spaced apart tension bolts extending substantially parallel to said shaft sections through said flanges and ring.

30 14. Apparatus for automatically centering a moving object according to claim 13, in which means are provided for keeping the outer surfaces of the large diameter ends of the rims in alignment.

35 15. Apparatus for positioning a moving object comprising a pair of coaxially opposed frustoconical rotatable rims over which the object passes in a direction transverse to the axes of the rims, the large diameter ends of said rims being adjacent each other, spaced coaxial shaft sections, a shaft extension for each of said shaft sections extending outwardly beyond said rims and adapted to be supported in bearing means, the large diameter ends of said rims being movable toward the axis of said shaft sections progressively at the points or lines of contact with the moving object on the approach side, an operative connection between the small diameter end of each of said rims and the adjacent shaft sections, means extending inwardly from each of said rims, and spaced apart tension bolts extending substantially parallel to the axis of said shaft sections through said last named means for urging the large diameter ends of said rims toward each other.

40 16. Apparatus for positioning a moving ob-

ject comprising a pair of coaxially opposed frusto-conical rotatable rims over which the object passes in a direction transverse to the axes of the rims, the large diameter ends of said rims being adjacent each other, spaced coaxial shaft sections, a shaft extension for each of said shaft sections extending outwardly beyond said rims and adapted to be supported in bearing means, the large diameter ends of said rims being movable toward the axis of said shaft sections progressively at the points or lines of contact with the moving object on the approach side, an operative connection between the small diameter end of each of said rims and the adjacent shaft section, said connection including a web portion for supporting the small diameter end of each of said rims, and spaced apart tension bolts extending substantially parallel to the axis of said shaft sections through said web portions.

17. Apparatus for positioning a moving object comprising a pair of coaxially opposed frusto-conical rotatable rims over which the object passes in a direction transverse to the axes of the rims, the large diameter ends of said rims being adjacent each other, spaced coaxial shaft sections, a shaft extension for each of said shaft sections extending outwardly beyond said rims and adapted to be supported in bearing means, the large diameter ends of said rims being movable toward the axis of said shaft sections progressively at the points or lines of contact with the moving object on the approach side, an operative connection between the small diameter end of each of said rims and the adjacent shaft section, said connection including a web portion for supporting the small diameter end of each of said rims, a flange extending inwardly from the large diameter end of each of said rims, and spaced apart tension bolts extending substantially parallel to the axis of said shaft sections through said web portions and said flanges.

18. Apparatus for positioning a moving object comprising a pair of coaxially opposed frusto-conical rotatable rims over which the object passes in a direction transverse to the axes of the rims, the large diameter ends of said rims being adjacent each other, spaced coaxial shaft sections, a shaft extension for each of said shaft sections extending outwardly beyond said rims and adapted to be supported in bearing means, the large diameter ends of said rims being movable toward the axis of said shaft sections progressively at the points or lines of contact with the moving object on the approach side, an operative connection between the small diameter end of each of said rims and the adjacent shaft section, said connection including a web portion for supporting the small diameter end of each of said rims, a ring adjacent each of said web portions, spaced apart tension bolts extending substantially parallel to the axis of said shaft sections through said rings, and driving means connecting each of said web portions to the ring adjacent thereto.

19. Apparatus for positioning a moving object comprising a pair of coaxially opposed frusto-conical rotatable rims over which the object passes in a direction transverse to the axes of the rims, the large diameter ends of said rims being adjacent each other, spaced coaxial shaft sections, a shaft extension for each of said shaft sections extending outwardly beyond said rims and adapted to be supported in bearing means, the large diameter ends of said rims being movable toward the axis of said shaft sections pro-

gressively at the points or lines of contact with the moving object on the approach side, an operative connection between the small diameter end of each of said rims and the adjacent shaft section, said connection including a web portion for supporting the small diameter end of each of said rims, a ring adjacent each of said web portions, a ring bearing against the inner surface of the large diameter end of each of said rims, spaced apart tension bolts extending substantially parallel to the axis of said shaft sections through said rings, and driving means connecting each of said web portions to the ring adjacent thereto.

20. Apparatus for positioning a moving object comprising a pair of coaxially opposed frusto-conical rotatable rims over which the object passes in a direction transverse to the axes of the rims, the large diameter ends of said rims being adjacent each other, spaced coaxial shaft sections, a shaft extension for each of said shaft sections extending outwardly beyond said rims and adapted to be supported in bearing means, the large diameter ends of said rims being movable toward the axis of said shaft sections progressively at the points or lines of contact with the moving object on the approach side, an operative connection between the small diameter end of each of said rims and the adjacent shaft section, said connection including a web portion for supporting the small diameter end of each of said rims, a ring adjacent each of said web portions, and spaced apart tension bolts extending substantially parallel to the axis of said shaft sections through said rings.

21. Apparatus for positioning a moving object comprising a pair of coaxially opposed frusto-conical rotatable rims over which the object passes in a direction transverse to the axes of the rims, the large diameter ends of said rims being adjacent each other, spaced coaxial shaft sections, a shaft extension for each of said shaft sections extending outwardly beyond said rims and adapted to be supported in bearing means, the large diameter ends of said rims being movable toward the axis of said shaft sections progressively at the points or lines of contact with the moving object on the approach side, an operative connection between the small diameter end of each of said rims and the adjacent shaft section, said connection including a web portion for supporting the small diameter end of each of said rims, an inwardly extending flange fastened to each of said rims a short distance from the large diameter end thereof, an elastic ring between said flanges, and spaced apart tension bolts extending substantially parallel to said shaft sections through said flanges and ring.
